UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

CLASP-BRAKE BEAM.

1,207,254.

Specification of Letters Patent.

Patented Dec. 5, 1916.

Application filed July 13, 1916. Serial No. 109,137.

To all whom it may concern:

Be it known that I, CHARLES HAINES WILLIAMS, a citizen of the United States, residing at the city of Chicago, county of Cook, and State of Illinois, have invented a certain new and useful Improvement in Clasp-Brake Beams, of which the following is a full, clear, and exact description, such as will enable others skilled in the art to 10 which it appertains to make and use the same, reference being had to the accompanying drawings, forming part of this specification, in which—

Figure 1 is a plan view of one end of my 15 improved brake beam designed especially for clasp brakes. Fig. 2 is a front elevational view. Fig. 3 is a vertical sectional view on line 3—3 of Fig. 1. Fig. 4 is a sectional view on line 4—4 of Fig. 1. Fig. 20 5 is a plan view of another form of my invention. Fig. 6 is a front elevational view of the structure shown in Fig. 5. Fig. 7 is a vertical sectional view on line 7—7 of Fig. 5. Fig. 8 is a plan view of another 25 modified form of my invention. Fig. 9 is a sectional view on line 9—9 of Fig. 8.

This invention relates to a new and useful improvement in brake beams designed especially for clasp brakes in that the beam 30 is provided with a strut or post near each end for the attachment of the brake applying devices. It is obvious, however, that a single strut or post could be employed at the center of the beam so that it could be 35 used in connection with ordinary brake mechanism.

The object of my present invention is to utilize a commercially rolled flange form as the principal beam member. This may be 40 an I beam, channel, or other structural or pressed shapes. The ends of this member are provided with reinforcements in the form of pressed, cast, or forged pieces riveted or otherwise secured to the main 45 beam member, and providing trunnions or mounts for the brake heads. The posts or struts are secured to these reinforcements and consequently when power is applied to the brake heads through these posts or 50 struts, it will be transmitted through these

reinforcements augmented by the strength of the main beam member.

In the drawings 1 indicates the main beam member, here shown as an I beam, having its ends slightly compressed but these ends 55 may be straight if desired.

In Figs. 1 to 3, 2 indicates pressed metal reinforcing members whose shank extensions are riveted to the web of the beam 1 and whose outer ends are formed so that when 60 the parts are assembled a trunnion 3 is provided, thereby constituting a mount for the brake head, and an extension 4 is likewise formed which may be threaded to receive a nut whereby the brake head is held in 65 place. When these pressed metal parts are assembled on the beam they may be machine finished. 6 are pressed metal plates riveted together and to the shanks of the reinforcing members 2. These plates are 70 riveted at their outer ends to provide means for the attachment of the brake applying devices.

In Figs. 5 to 7, I have shown the reinforcing members as being integral with the 75 trunnion 7, and in this form a single casting or forging may be used instead of separated pressed plates shown in Figs. 1 to 3.

In Fig. 8, I have shown reinforcing members as being cast integral with the ratchet 80 trunnion 8 designed especially for an adjustable brake head. In this form the strut or post is in the form of a casting 9 having a vertically disposed opening.

I claim:

1. In a brake beam the combination of a main beam member, reinforcing elements arranged on each end thereof and carrying mounts for the brake heads, and separate or independent struts or posts connected to 90 said reinforcing elements.

2. In a brake beam the combination of a commercially rolled flange member, reinforcing elements arranged on each side thereof at the ends of the beam, said reinforcing elements providing mounts for the 95 brake heads, and struts or posts connected to said reinforcing elements.

3. In a brake beam the combination of a main member and end members divided to 100

receive said main member and reinforcing
the same at the ends of the beam, said end
members providing mounts for the brake
heads, and struts or posts connected to the
5 inner ends of said divided reinforcing mem-
bers.

In testimony whereof I hereunto affix my

signature in the presence of two witnesses,
this seventh day of July, 1916.

CHARLES HAINES WILLIAMS.

Witnesses:

E. T. WALKER,
M. F. HUNTOON.
